UNITED STATES PATENT OFFICE.

MICHAEL FISCHER, OF RICHMOND, CALIFORNIA.

WELDING-TORCH.

1,276,893.

Specification of Letters Patent. Patented Aug. 27, 1918.

Application filed May 6, 1918. Serial No. 232,915.

To all whom it may concern:

Be it known that I, MICHAEL FISCHER, a citizen of the United States, residing at Richmond, in the county of Contra Costa and State of California, have invented certain new and useful Improvements in Welding-Torches, of which the following is a specification.

My invention relates to torches for heating metals in the welding, cutting and other treatment thereof, and particularly to torches the flame of which is produced by a mixture of oxygen and acetylene gases.

My invention consists in certain improvements in oxy-acetylene torches of the low pressure injector type, in which the mixing chamber is located in the body of the torch, in contradistinction to its location in the tip as in high-pressure torches; and being so located in the body is non-interchangeable.

The objects of my improvements generally stated are to provide, in a low-pressure injector torch, means for thoroughly and intimately mixing the gases in order to obtain the theoretically correct proportions of the mixture, namely one to one in volume; also to provide simple and efficient means for preventing flash backs entering the initial mixing chamber; and, finally, to provide means tending to insure the stability of the mixture.

These objects together with the means for attaining them will now fully appear from the following description of my torch taken in connection with the accompanying drawings in which:

Figure 1 is a side elevation partly in section of my torch.

Fig. 2 is a longitudinal section enlarged and broken of the same.

Fig. 3 is a longitudinal section of the tip.

The handle member comprises an outer shell 1, an inner tube 2 for the oxygen, an inner tube 3 for the acetylene, and a handle-head 4 fitted to and uniting said shells and tubes in such manner that the tubes are spaced both from the shell and from each other. The handle head is formed with a socket connection 5 for the oxygen supply, and with a socket connection 6 for the acetylene supply. A duct 5' in the head leads to the oxygen tube 2 and a duct 6' leads to the acetylene tube 3. To the other end of the handle member is fitted the regulating-valve-shell 7 in which is

located the needle-valve seat-member 8, as seen in Fig. 2. A duct 9 in the shell 7 leads from the acetylene tube 3 to a space 10 surrounding the rear end of the seat-member 8, said space 10 communicating with an encircling groove 11 of said seat-member, and said groove communicates with channels 12 formed in the forward angular end of the seat-member, which channels lead into grooves 13 in the tip of the seat-member, said grooves leading into the chamber 14 of the mixing-member 15, which latter is fitted to the shell 7.

It will thus be seen that the course of the acetylene is from the connection 6, through the duct 6', tube 3, duct 9, space 10, groove 11, channels 12, and grooves 13 into the mixing chamber 14.

In the seat-member 8 is the regulating needle-valve 16, held open normally by a spring 17, and adjusted by a screw 18 fitted in the wall of the shell 7 and having its inner end bearing on the inner end of the shank 16' of the needle valve.

A duct 19 in the shell 7 leads from the oxygen tube 2 of the handle member to the interior shell space 7' which space communicates with grooves 20 on the inner end of the needle-valve shank 16', said grooves 20 communicating with a helical groove 21 of the valve which last named groove opens out at the valve tip.

Thus the course of the oxygen is from the connection 5, through the duct 5', tube 2, duct 19, space 7', and grooves 20 and 21, into the mixing chamber 14, and the volume of oxygen is controlled by the needle valve 16, as regulated by the screw 18.

The two gases thus unite in the mixing chamber 14 and the proportion of each regulated and controlled.

Now, in order to effect the thorough and intimate mixture of the gases, the following means are employed. The mixing-chamber member 15 has at its forward end a bore 15', which at its inner end conically decreases at 15'' to meet the mixing chamber 14. In the inner end of the bore 15' is fitted a mixing plug 22, the base of which is concaved at 22' complementally to and lies opposite the concavity 15'' at the base of the bore 15'. The forward end of the plug 22 is likewise concaved at 22'', and in said plug are made the ducts 23 in annular series near its periphery, said ducts leading from the concavity 22' and joining inwardly in

clined ducts 23' which lead into the cavity 22'.

A second mixing plug, similar in all respects and indicated by like numerals, lies 5 immediately in front of and co-operates with the first plug.

In front of the second plug is a third mixing plug 24, the forward end of which is like the previous plugs, but its rear portion 10 has an exterior helical channel 25, communication with the rear end of which is had through the holes 26 leading outwardly from its axis. The forward end of the helical channel 25 communicates with the ducts 15 of the forward portion of the plug 24.

27 is a coupling sleeve, holding all these plugs in place and also connecting up the jacket 28 of the nozzle member. The nozzle member comprises the jacket 28 and the inner tube 29 spaced from the jacket. A hole 29' leads into the jacket space. The inner tube 29 communicates at its rear end with the final mixing plug, and at its forward end it has fitted to it the tip 30. The tip has a 25 spaced jacket 31.

The course of the united gases may now be traced from the initial mixing chamber 14. This course is outwardly, forwardly, and inwardly through the first two plugs, helically 30 about the rear portion of the third plug, and forward and inwardly through its forward portion and thence through the nozzle tube and tip. In this tortuous course an intimate mixture is had and maintained; and, 35 moreover, these plugs prevent back-firing, which is choked by the intricate passage thus formed, and is not likely to ever reach the initial mixing chamber 14.

The jacketing of the nozzle, has two effects, namely it tends to cool the nozzle, (which may be by air or water) so as to reduce the tendency to back-fire, and also, by such cooling it prevents the tendency of the inner nozzle tube 29 to expand under heat and 40 thereby tend to affect the stability of the mixture passing through it. The jacketing of the tip 30 in like manner contributes to these results. The needle valve control provides for increasing or decreasing the area 45 of the orifice of the oxygen injector as needed for the different sizes of interchangeable tips.

It is now proven in practice that a consumption of one volume of acetylene to one 55 volume of oxygen results in a saving of from three to ten cubic feet per hour of welding, depending on the size of tip used. The proportion may be had and maintained in this torch, and gives a greater stability to the 60 flame.

I claim:

1. A torch for the described purpose comprising a handle member provided with separate connections and passages for the 65 gases; a mixing-chamber-member into

which said passages separately lead; a controllable injector assemblage intermediate the handle member and mixing-chamber-member consisting of a shell fitted to the handle-member, a needle-valve-seat member in the shell, a spring-controlled normally retracted needle-valve in the seat-member, and an adjusting screw fitted in the side wall of the shell and bearing on the rear end of the needle-valve; a series of plugs in said 70 mixing-chamber-member formed with communicating ducts constituting a tortuous mixing passage leading from the mixing-chamber of said member; and a nozzle member fitted to the mixing chamber member. 80

2. A torch for the described purpose comprising a handle member provided with separate connections and passages for the gases; a mixing-chamber-member into which said passages separately lead; a controllable injector intermediate the handle member and mixing-chamber-member; a series of plugs in said mixing-chamber-member formed with communicating ducts 85 constituting a tortuous mixing passage leading from the mixing-chamber of said member, said series of plugs comprising concave-ended members with an annular series of body ducts and inwardly directed delivery ducts and an intervening portion with a helical peripheral groove; and a nozzle member fitted to the mixing chamber member. 95

3. A torch for the described purpose comprising a handle member provided with separate connections and passages for the 100 gases; a mixing-chamber-member into which said passages separately lead; a controllable injector intermediate the handle member and mixing-chamber-member; a series of plugs in said mixing-chamber-member formed with communicating ducts 105 constituting a tortuous mixing passage leading from the mixing-chamber of said member, said series of plugs comprising concave-ended members with an annular series of body ducts and inwardly directed delivery ducts, and an intervening portion with a helical peripheral groove; and a nozzle member fitted to the mixing chamber member, said nozzle member being jacketed. 110

4. In a torch for the described purpose, having an initial mixing chamber into which the two gases are separately delivered, a series of plugs succeeding the mixing chamber, said series comprising concave-ended members with an annular series of body ducts and inwardly directed delivery ducts, and an intervening portion with a helical peripheral groove, said ducts and groove forming a tortuous mixing passage. 115

5. In a torch for the described purpose, having an initial mixing chamber into which the two gases are separately delivered, a series of plugs succeeding the mixing chamber, said series comprising concave- 120

- ended members with an annular series of body ducts and inwardly directed delivery ducts, and an intervening portion with a helical peripheral groove, said ducts and groove forming a tortuous mixing passage; a nozzle-member fitted to the mixing-chamber-member; and a tip fitted to the nozzle-member, said nozzle member and tip being jacketed.
- 10 6. A torch for the described purpose comprising a handle member provided with separate connections and passages for the gases; a mixing-chamber-member into which said passages separately lead; a controllable injector assemblage intermediate the handle member and mixing-chamber-member; said injector assemblage comprising a shell fitted to the handle member, a valve-seat member in said shell around which one of the gases passes, a normally retracted spring-controlled needle valve in said valve seat member having a helical peripheral groove through which the other gas passes and an adjusting screw fitted in the side wall of the shell and bearing on the inner end of the needle-valve; and a nozzle member fitted to the mixing chamber member.
- 15 In testimony whereof I have signed my name to this specification in the presence of two subscribing witnesses.
